(57) **CLAIM**

The ornamental design of a dispenser and chemical cartridge combination, as illustrated in the drawings.

DESCRIPTION

FIG. 1 is an assembled perspective view of the dispenser and chemical cartridge combination of the present invention; FIG. 2 is a top plan assembled view of the dispenser and cartridge;

FIG. 3 is a front elevation assembled view of the dispenser and cartridge;

FIG. 4 is a bottom plan assembled view of the dispenser and cartridge;

FIG. 5 is a left side elevation assembled view of the dispenser and cartridge;

FIG. 6 is a right side elevation assembled view of the dispenser and cartridge;

FIG. 7 is a back elevation assembled view of the dispenser and cartridge;

FIG. 8 is an exploded perspective view of the dispenser and chemical cartridge of the present invention;

FIG. 9 is a front elevation exploded view of the dispenser and cartridge;

FIG. 10 is a back elevation exploded view of the dispenser and cartridge;

FIG. 11 is a right side elevation exploded view of the dispenser and cartridge; and,

FIG. 12 is a left side elevation exploded view of the dispenser and cartridge.
